NECKTIE HANGER

Maurice E. Lessin, Bronx, N. Y.

Application August 31, 1943, Serial No. 500,685

8 Claims.

(Cl. 211—7)

The present invention relates to improvements in necktie hangers and has for an object to improve that type of domestic hanger employed in the household to the end that the hanger may accommodate large numbers of neckties, yet be susceptible of folding compactly and neatly into an unobtrusive position against a wall or other support.

Another object of the invention resides in providing an improved necktie hanger and coordinate enclosing and operating frame capable of an enfolded position of storage for the necktie, and movable to an outward displaying position where the neckties are revealed openly and in a single line, where all of the neckties may be viewed and inspected, with reference to one another, to the end that a proper color selection may be made for the purpose of matching suits and other garments.

A further object of the invention is to provide a combined support, foldable necktie hanger and operating member, so constructed and arranged, and so related that the support sustains both the necktie hanger and the operating member, and the latter is coupled to the necktie hanger in a manner to draw the hanger outwardly to extended position on the outward swinging movement of such operating member with reference to the support.

A still further object of the invention is to so construct and arrange and relate a support, necktie hanger, and its operating member, that the operating member will outstand from the support in a manner to afford an enclosing space into which the necktie hanger may nest and fold, and in which the operating member is so related to the support as to provide for a latching engagement between the two, when the operating member and necktie hanger are moved to the folded position.

Other objects of the invention are to simplify the construction of necktie hangers and their supports, to decrease the cost of construction while improving the rigidity, strength and sustaining abilities of the hanger bars, to increase the capacities of the hangers, to enhance the appearance of such articles, and to condense the same in overall structure to fit in cramped spaces heretofore unavailable for such purposes.

With the foregoing and other objects in view, which will be readily apparent to those skilled in the art, the invention will be more fully described hereinafter and more particularly pointed out in the appended claims.

In the drawing, in which like reference char-

acters designate like parts throughout the several views:

Figure 1 is a front elevation of an improved necktie hanger constructed in accordance with the present invention;

Figure 2 is a top plan view of the same, showing in full lines the folded position, and in dotted lines the extended position of the improved hanger and its operating and imposing member;

Figure 3 is a vertical longitudinal section taken through the improved hanger and its operating member along the line 3—3 in Figure 2; and

Figure 4 is a horizontal section taken on the line 4—4 in Figure 1, on an enlarged scale.

Referring more particularly to the drawing, which shows one embodiment of which the invention is susceptible, W indicates a wall to which may be attached the support 11 in any suitable form, for instance a bar, plate or the like.

The operating and enclosing member is designated generally 10, the same being pivoted at one end portion, as indicated at 12, to an end portion of the plate 11. Such support 11 has also at its end portions, perforated lugs 13 and 14 through which screws 30 or other fastening means pass, for entering the wall W.

The necktie hanger is, in the instance illustrated, composed of two members or sections 15 and 16, which may be in the form of bars of metal, wood or other appropriate material having upstanding pins 17 and 18 spaced appropriate distances in pairs to confine therebetween intermediate portions of the ties T, as indicated in broken lines in Figure 3.

The tie bars 15 and 16 are mutually pivoted at 19 for swinging out into the dotted line position shown in Figure 2. The other end of the outer tie bar 15 is pivoted, as at 20, to a hinge member 20a carried by the operating member 10. Associated with this hinge member 20a is a knob or handle 10a on the operating member 10, for convenience in grasping this member and drawing the same outwardly to the dotted position shown in Figure 2 and for moving the same back to the full line collapsed position.

The right hand end of the inner tie bar 16 is pivoted at 21 to the hinge or pintle member 21a, screw threaded or otherwise fixed to the supporting or backing bar 11. A resilient keeper 22 on the free end of the operating member 10 has an offset portion 31 for snapping back of a mutually offset lug 23 carried by the supporting member 11.

As shown in Figure 2, the operating member 10

is shown in full lines in substantial parallelism with the base or support 11 and with the two bars 15 and 16, making up the necktie hanger; however this operating member 10 is spaced sufficiently in front of the support 11 to provide ample accommodation for the enfolded tie hanger bars 15 and 16. Structurally, this arrangement is achieved by the fact that the pivot or hinge 12 is mounted between a forwardly offset lug 32 of the support 11 and an inturned end portion 33 of the operating member 10. These two offsets 32 and 33 set off or displace the axis or fulcrum of the hinge pintle 12 from the planes of both members 10 and 11 whereby the member 10 outstands from the member 11 for the purpose of providing ample space between the members for containing the tie bars 15 and 16, and for the additional purpose of freeing the hinge 12 for clearance in the pivotal movement of the member 10, and particularly for the clearance of the offset portion 33 thereof, for which compare the full and the dotted line portions of the member 10 in Figure 2.

At the free end of the member 10, the catch or latch 22 forms a complement of the offsets 32, 33 in that its inner end forms a stop cooperating with the support 11 to limit the inward swinging movement of the operating member 10 beyond a point where the tie bars 15 and 16 reach a fully collapsed position, to prevent these tie bars from moving so far together as to crush the ties one upon another, or upon the bars themselves. Thus the latch 22 performs a double function, that of a keeper and stop member. This latch member may be made of rigid material if desired, in which case the keeper 23 will possess some degree of resiliency, to enable it to give, when the operating member 10 is pushed home.

In order to retain the tie hanging members 15 and 16 in substantial parallel relation when collapsed, with sufficient spacing therebetween to avoid crushing the ties and to permit the ties to hang independently of one another, the left hand ends of each of such bars 15 and 16 are offset mutually toward one another so that the axis of the pintle hinge 19 lies in the extended plane which passes between the two members 15 and 16. The other ends 20 and 21 are prevented from movement together by the stop action of the latch 22.

By placing the handle or knob 10a at the free end of the operating member 10, the arrangement gives greater leverage in the operation and also enables a single escutcheon plate 34 to mask the threaded shanks of both members 10a and 20a.

In operation, the handle or knob 10a is grasped and forcibly pulled outwardly away from the support 11, which will thus act to cause release of the latch members 22 and 23. The continued outward swinging movement of the operating member 10 about its hinge 12 will act to draw out the hinge member 20a and the entrained end 20 of the tie bar 15. This member 15 may first rotate about the pintle 19, but the difference in distance or displacement of hinges 12 and 19 will cause the operating member 10 at a certain angular displacement of its opening movement, to pick up the tie bar 16 and rotate it about its hinge pintle 21. The pintle 21 being stationary, and the pivots 19 and 20 being movable, by movements of translation, the two members 15 and 16 of the hanger may be drawn out to the broken line position shown in Figure 2.

These hitherto parallel members 15 and 16 now

extend in a straight line and form the hypotenuse of a triangle, of which the members 10 and 11 form the other two sides. Moreover, the right line or straight line rearrangement of tie sustaining bars 15 and 16 constitutes a toggle lock, in that pivots 19, 20 and 21 are all in the same line. Such toggle lock will prevent the device from casual or accidental collapse as the ties will be viewed from the outside of the tie hanger and 10 the action of the user in removing and replacing the neckties will be apt to collapse the device. The ties will be simply draped over the bars 15 and 16 between pairs of the upstanding pegs or pins 17 and 18. In this way a large number of 15 ties of different colors and assortments may be brought simultaneously into view over the length of the comparatively long hanger, in that the hypotenuse is the longest side of the right angle triangle. Moreover, where the hanger is constituted of a single straight line bar, ease is promoted 20 in the placing and removal of ties, and one tie is not calculated to interfere with another one.

After the selection has been made and the necessary ties removed or replaced, by pushing inwardly upon the intermediate portion of the hanger member in and about the intermediate hinge 19, the toggle lock will be broken, which permits the operating member 10 to be then returned in the opposite direction, pushing before 30 it the hinge member 20a and the articulated members of the tie hanger until all of the parts are returned to the enfolded position; whereupon with the exertion of slight force the latch members 22 and 23 may be caused to reengage one 35 another. The member 10 provides not only an operating member but also an enclosing member for the bars. Of course the lower portions of the ties may or will project below this enclosed space. The front face of the member 10 may be 40 embellished in any suitable manner or may be made to conform to any desired design or ornamental characteristics, blending in with that of other furniture or furnishings.

I claim:

- 45 1. A necktie hanger comprising a pair of tie-rack sections hinged together at one end, a support, and an operating member, said operating member being pivoted at one end to one end of the support, the other end of one of said sections being pivoted to the opposite end of 50 the support, the other end of the other of said sections being pivoted to the free end portion of said operating member.
- 55 2. A necktie hanger as claimed in claim 1, characterized by the fact that the pivot between the operating member and support is spaced from the pivot connecting the tie-rack sections.
- 60 3. A necktie hanger as claimed in claim 1, wherein a latch member cooperates with said support to limit the inward swinging movement of the operating member.
- 65 4. A necktie hanger as claimed in claim 1 in which relatively resilient latch members one on the support and one on the operating member act to yieldably retain the operating member in closed position, one of said latch members constructed and arranged with reference to said support to act as a stop to limit the inward swinging movement of the operating member.
- 70 5. A necktie hanger comprising a support, an enclosing member pivoted at one end portion to an end portion of the support, complementary latch parts between the support and free end portion of said member, a pair of hanger sections pivoted together at one end, the other end

of one hanger section pivoted to the opposite end portion of the support from that to which said member is pivoted, the other end of the other hanger section pivoted to the free end portion of said member.

6. A necktie hanger comprising a support, an enclosing member having an end pivoted to an end portion of the support in offset relation to the support to fold into substantial parallelism therewith, combined latch and stop means between said support and the free end portion of said enclosing member to arrest the inward motion of the member and to retain the same in such parallel relation, and a pair of tie-rack sections nested into the space between said support and member, said sections being pivoted together at one end, the other end of one section being pivoted to the support at the opposite end portion from that to which said member is pivoted, the other end of the other section being pivoted to the free end portion of said member.

7. A necktie hanger comprising a fixed sup-

port, a pair of tie-rack bars pivoted together at one end in offset relation to enable same to assume a spaced substantially parallel relation, one bar pivoted at its other end to an end portion of said support on a pivot axis outstanding from the front plane of said support, and an operating and enclosing member pivoted at one end to the opposite end portion of said support in outwardly offset relation to said support and at a distance from the pivotal connection between the bars, the other bar pivoted at its other end to said member near but displaced from the free end of said member.

8. A necktie hanger as claimed in claim 7, characterized by a stop at the free end portion of the operating member adapted to strike said support when the member reaches a closed position, and detent means between said member and support to yieldably retain the same in said closed position.
